[57] **CLAIM**

The ornamental design for a combined typewriter and portable calculator, as shown and described.

DESCRIPTION

FIG. 1 is an exploded front perspective view of a combined typewriter and portable calculator showing my new design;

FIG. 2 is a top, right perspective view with the calculator inserted;

FIG. 3 is a rear elevational view.

FIG. 4 is a right side elevational view with the calculator partially withdrawn.

The left side is a mirror image of the right.
